UNITED STATES PATENT OFFICE

WILLIAM J. ADAMS, OF SANTA CRUZ, CALIFORNIA, ASSIGNOR TO BALL WAGON GRADER COMPANY, OF STOCKTON, CALIFORNIA, A CORPORATION

CHAIN DRIVE CONTROL FOR SCRAPER BOWLS

Application filed September 28, 1928. Serial No. 308,995.

This invention relates to devices for controlling the raising and lowering of scraper bowls and particularly represents improvements over the control structure for this purpose shown in the patent to Charles E. and Samuel H. Ball, No. 1,593,007, dated July 20, 1926.

The control structure consists essentially of a sheave connected in driving relation with a ground engaging wheel of the supporting frame of the scraper, a sprocket wheel, an endless chain about the sprocket and sheave, a hand controlled idler sheave for tightening the chain so that it will frictionally engage the other sheave and cause the sprocket to be rotated, and operating connections between the sprocket and the scraper bowl to cause the latter to be raised when the sprocket is thus rotated. This provides very smooth operating mechanism for controlling the raising and lowering of the bowl and was much cheaper than a disc clutch or a similar mechanism. In the previous device however, the chain was of the ordinary roller type having the usual narrow side plates on the links, and as a result these plates soon cut grooves in the sheave unduly wearing same, and themselves wearing out very quickly so that frequent link replacements were necessary.

Also the small area of contact of the chain link plates with the sheave necessitates a very heavy pressure being placed on the idler to obtain the desired working engagement of the chain with the sheave. The principal object of the present invention is to avoid these objectionable and defective features by constructing the chain so that the sheave will not become grooved and the chain links will not wear out so fast, and less pressure on the control idler is necessary to obtain the proper non-slipping adhesion of the chain on the sheave.

A further object of the invention is to produce a simple and inexpensive device and yet one which will be exceedingly effective for the purpose for which it is designed.

These objects I accomplish by means of such structure and relative arrangement of

parts as will fully appear by a perusal of the following specification and claims.

In the drawings similar characters of reference indicate corresponding parts in the several views:

Fig. 1 is a side elevation of a portion of a scraper structure equipped with my improved chain control device, the near wheel being removed.

Fig. 2 is an enlarged fragmentary section 60 of the special chain and sprocket wheel.

Fig. 3 is a similar view of the chain and sheave.

Fig. 4 is a fragmentary plan view of the chain.

Referring now more particularly to the characters of reference on the drawings, the numeral 1 denotes the main side frames of the scraper, which support a transverse axle 2 adjacent its rear end, on which the ground engaging wheels 3 and a large grooved sheave 4 are mounted in common driving relation. The scraper bowl 5 is suspended between the frames 1 by links 6 and is raised by cable elements 7 passing from the bowl 75 over sheaves 8 to a drum 9 mounted on a transverse shaft 10 disposed above the axle 2. It is here to be noted that the shape and mounting of the bowl, and the particular form of connection between the bowl and 80 the shaft 10 may be varied considerably, since they form no part of the present invention and are merely shown for purposes of illustration.

Fixed on the shaft 10 is a sprocket wheel 85 11 having teeth 12 spaced to engage only alternate links 13 of the chain which passes about the sprocket wheel and the sheave 4. The intermediate links 14 of the chain have solid web plates 15 extending across the 90 space between the side plates of said links and disposed on the edges thereof adjacent the sheave. This arrangement as will be evident provides a much greater area of contact with the sheave than the narrow plates 95 themselves, and said webs are preferably curved on an arc the same as the curvature of the sheave so as to contact therewith over their entire area. These webs are set inwardly of the plane of the adjacent edges of 100

the side plates of the links 13 as shown in Fig. 3, so that such plates will not engage and cut into the sheave.

These intermediate links are preferably the widest ones of the chain, so that the area of the web plates is as great as possible without extending them beyond the sides of the link plates.

The sprocket wheel between the teeth is recessed as at 16 to receive the plates 15 therebetween without contacting, and the teeth at their roots are provided with shoulders 17 projecting under the tooth engaging rollers 18 of the chain to hold said chain in its proper position relative to the teeth and prevent the latter from possibly wedging between adjacent rollers.

Normally the sheave rotates without imparting movement to the chain, the latter being loose enough to ride free. To place the chain plates 15 in frictional driving relation with the sheave when desired, in order to cause the sprocket wheel to be rotated, an idler sheave 19 is mounted on one end 25 of a hand controlled lever 20, pivoted intermediate its ends on the frame 1, said idler being positioned to engage the outer face of the chain intermediate the sprocket and sheave, as in said aforementioned patent. 30 While I have here shown and described this arrangement as being particularly intended to control the movement of a scraper bowl, it will be obvious that its use is not limited to this purpose, since it can be employed to 35 control the rotation of the sprocket wheel for any purpose desired.

From the foregoing description it will be readily seen that I have produced such a device as substantially fulfills the objects of 40 the invention as set forth herein.

While this specification sets forth in detail the present and preferred construction of the device, still in practice such deviations from such detail may be resorted to as do 45 not form a departure from the spirit of the invention, as defined by the appended claims.

Having thus described my invention what I claim as new and useful and desire to 50 secure by Letters Patent is:

1. In combination, a sheave, a sprocket wheel, an endless chain about the sprocket and sheave, the teeth of the wheel engaging only alternate links of the chain, and cross plates on the intermediate links to engage the face of the sheave throughout their area and projecting from the sheave engaging sides of the links to maintain said alternate links clear of the sheave.

2. In combination, a sheave, a sprocket wheel, an endless chain about the sprocket and sheave, and plates fixed on the intermediate links and extending laterally thereof to engage the face of the sheave; said 65 plates being curved on an arc equal to that

of the curvature of the sheave to enable said plates to bear for their full area against the sheave.

3. A chain for use about a sprocket wheel comprising links having side plates, and webs extending between the side plates of alternate links, said webs projecting outwardly of the adjacent edges of the side plates of the intermediate links from the same side of the chain as that adapted to 75 lie against the wheel.

4. A structure as in claim 1 in which the sprocket wheel, at the base of the teeth, is recessed to receive the plates in clearance relation when said plates are passing about 80 the wheel.

In testimony whereof I affix my signature.

WILLIAM J. ADAMS.
